UNITED STATES PATENT OFFICE.

RAYMOND H. SULLIVAN, OF ROCHESTER, NEW YORK, ASSIGNOR TO NORTH EAST ELECTRIC COMPANY, OF ROCHESTER, NEW YORK, A CORPORATION OF NEW YORK.

TEMPERATURE COMPENSATION FOR ELECTRIC INSTRUMENTS.

1,411,311.

Specification of Letters Patent.

Patented Apr. 4, 1922.

Application filed December 16, 1919. Serial No. 345,369.

To all whom it may concern:

Be it known that I, RAYMOND H. SULLIVAN, a citizen of the United States, residing at Rochester, in the county of Monroe and 5 State of New York, have invented certain new and useful Improvements in Temperature Compensation for Electric Instruments; and I do hereby declare the following to be a full, clear, and exact description of the invention, such as will enable others skilled 10 in the art to which it appertains to make and use the same.

This invention relates to means by which the effect of varying temperature, upon the 15 action of an electro-magnetic instrument such as a relay or an automatic regulator for a dynamo, may be neutralized, either in part or completely, or even over-compensated if desired.

20 The object of the invention is to accomplish the desired compensation solely by means of suitably balanced resistances of different temperature-coefficients, and particularly to avoid the necessity of using inordinate amounts of resistance or materials having either negative or unusually high temperature coefficients.

It has been proposed to accomplish the 30 result in question by means of a resistance in series with the winding which is to be compensated, and a second resistance in parallel therewith, the first of these resistances having a low or approximately 0 coefficient and the second having a coefficient higher 35 than that of the winding. This arrangement, while theoretically correct, is impractical for most uses because if the winding is of copper, which is the only satisfactory material for commercial purposes, it is impossible to find any material having a sufficiently higher coefficient for use in the parallel resistance. Where the winding is of copper, therefore compensation can be secured in the manner described only by the 40 use of an inordinate amount of resistance in all parts of the system.

The present invention is a novel arrangement of resistances by which a winding of copper wire may be compensated by the use of 50 a moderate amount of resistance, and without the necessity of using any material having a higher coefficient than that of copper. This is accomplished by the expedient of lowering the temperature coefficient, as a whole, of 55 that branch of the circuit including the

winding, by introducing into that branch, in series with the winding, a resistance having a lower coefficient than that of the winding.

By the arrangement just described several valuable practical results are secured. In 60 the first place, only a moderate amount of resistance need be used. In the second place, the branch of the circuit in parallel with the winding need not have a higher coefficient than that of the winding, but may, 65 in fact be made of the same material. In the third place, the only resistance-material, other than copper, which is required is one having a relatively low coefficient, and materials of this character are readily available, 70 and have the advantages of high specific resistance and immunity from injurious atmospheric effects.

The invention consists in the combination of parts hereinafter described, and illustrated in the accompanying diagram, as it is defined in the annexed claims.

The drawing is a diagram showing the application of the invention to a relay used in regulating the voltage of a dynamo- 80 electric machine.

The invention is shown as applied to the compensation of a relay or regulating-device having an electro-magnet 1 provided with a winding 2, which may be of ordinary copper 85 wire. The armature 3 of the relay controls a short-circuit 4 around a regulating resistance 5. This resistance is connected in series with the shunt field-winding 6 of a dynamo 7, while the winding 2 of the relay 90 is connected, through compensating resistances, across the terminals of the dynamo, so that the relay opens the short-circuit upon the attainment of a predetermined voltage in the generator, thus throwing the resistance 95 5 into operation and regulating the voltage of the generator output in a well-known manner.

Three resistance-devices are employed in connection with the winding of the relay, 100 for the purpose of compensating for variations in temperature, whether of the atmosphere or due to the direct heating effect of the electric current upon the relay-winding. One of these resistance-devices 8 is immediately in series with the winding 2. This device is made of some material having a substantially lower temperature coefficient of resistance than the copper winding of the relay. Preferably its coefficient should be ap- 110

proximately zero, and for this purpose the material known as "thurlo" has been found suitable. The second resistance-device 9 has a comparatively high temperature coefficient, and this device may conveniently be made of copper wire, the same as the winding of the relay. This resistance-device 9 is connected in circuit parallel with both the winding 2 and the resistance-device 8.

10 The third resistance-device 10, which consists of thurlo or other material of low temperature coefficient, is arranged in series with the two parallel portions of the circuit already described. This resistance-device is

15 shown as connected, by a wire 11, with one of the main conductors 12 from the dynamo, the other main conductor 13 being connected, by a wire 14, with the common terminal of the resistance-devices 8 and 9.

20 The relay-winding and the resistance-device 9 should be so associated as to be always at substantially the same temperature, and a means for this purpose is indicated in the diagram as having the form of a casing 15

25 constituting a common inclosure for these parts. The resistance-devices 8 and 10 are shown as inclosed in the same casing, but this is not essential where the devices are of material having an approximately zero tem-

30 perature coefficient.

The operation of the compensating-devices may be described as follows: The total resistance of the resistance-devices and the relay-winding increases, with an increase of

35 temperature, at a much lower ratio than in the case of a winding of copper wire alone, owing to the presence of the resistance-device 10, and accordingly the flow of current at a given voltage is not greatly diminished

40 by such rise in temperature. The current, which divides between the resistance-device 9 and the resistance-device 8 and the winding 2, is distributed between these two branches of the circuit in accordance with

45 their relative resistances. With any rise in temperature the resistance of the device 9 increases more rapidly than that of the parallel portion of the circuit, owing to the fact that the latter consists only partly of

50 material of a high temperature coefficient. Accordingly, a rise in temperature results in an increased proportion of the current passing through the relay-winding 2, thus compensating for the diminution in the total

55 amount of the current.

By a suitable proportioning of the parts and selection of materials it has been found that a practically perfect compensation may be secured for any ordinary range of temperatures. By varying the proportions and materials an arrangement may be produced which will either over or under compensate, as circumstances render desirable. Where exact compensation is required it has been

65 found that this result may be secured by

making the relay-winding 2 and the resistance 9 of ordinary copper wire and the resistance-devices 8 and 10 of thurlo, the resistances of the parts 2, 8, and 10 being approximately equal, while the resistance of 70 the part 9 is 25% less.

The present invention has the advantage, among others, that it dispenses with the use of thermostatic devices and mechanisms of all kinds, and also that it does not call for 75 the use of material having a negative temperature coefficient of resistance.

It will be apparent that the invention is suitable for use with electric instruments and devices of various kinds, and that it 80 is not limited to the use of the particular resistance-materials specified in the preceding description.

The invention claimed is:

1. The combination, with an electric instrument having a conductor with a comparatively high temperature coefficient of resistance, of compensating devices comprising: a resistance-device, of low coefficient, in series with said conductor; a resistance-device, of high coefficient, in parallel with said conductor and the first-mentioned resistance-device; and a third resistance-device, of low coefficient, in series with the parallel-connected parts beforementioned. 85 90 95

2. A combination, as in claim 1, in which the respective resistances, at normal temperatures, of said conductor and the two resistance-devices of low coefficient are approximately equal, while the resistance of the device of high coefficient is approximately 100 three fourths as great.

3. The combination, with an electric instrument having a winding, of compensating devices comprising: a resistance-device, 105 having a substantially lower temperature coefficient than said winding, arranged in series therewith; a second resistance-device, having a coefficient not substantially lower than that of said winding, in parallel with 110 the winding and the first-mentioned resistance-device; and a third resistance-device, of substantially lower coefficient than that of said winding, in series with the parallel-connected parts beforementioned. 115

4. The combination, with an electric instrument having a winding of copper wire, of a resistance-device, having a temperature coefficient substantially lower than that of copper, in series with said winding; a resistance device, connected in parallel with the winding and the first mentioned resistance-device, having a coefficient higher than the joint coefficient of the winding and the first-mentioned resistance; and a resistance device in series with the before mentioned parallel branches of the circuit, the last-mentioned resistance-device having a coefficient lower than that of copper. 120 125
